STRIP HANDLING DEVICE

Fred J. Middlestadt, Baltimore, Md.

Application January 24, 1952, Serial No. 268,093

4 Claims. (Cl. 164—102)

This invention relates to material handling devices and more particularly to those used to carry finished material away from punch presses and the like.

While many arrangements have been suggested, designed and put in practice for the elimination of the manual handling of Venetian blind slats, after they have been operated on by the punch presses, the actual results have been wholly unsatisfactory, because all the devices mutilated the slats and scratched the paint therefrom. At the present time the material is painted, rolled and carried to the press, where it is cut to the proper lengths and holes are punched in them for the cords etc. but in all known instances the cut and shaped material is removed from the press by hand.

This invention avoids the manual handling of the finished slats and the defacing thereof and substitutes an automatic strip handling device to grasp the slot as soon as the press operations have been completed, and to carry it away from the press before the following slat enters the device.

One of the objects of this invention is to provide a new and improved material handling device for automatically removing venetian blind slats from a slat forming device.

It is a further object of this invention to provide a new and improved material handling device that will automatically bring the slat in frictional contact with a speeding roller at predetermined intervals to convey the material, while preventing burning the paint from the slat during the moving of said slat.

Other objects of the invention will become apparent as the invention is more fully set forth.

For a clearer understanding of the invention and the objects thereof, reference is made to the accompanying drawings, wherein a particular form of the invention is indicated. These drawings, when used in conjunction with the following description serve to illustrate the invention, its principles and the operation thereof, while the claims indicate the scope thereof.

In the drawings:

Figure 1 is a plan view of an automatic material handling device embodying this invention, with parts broken away to show its interior construction;

Figure 2 is a sectional view taken along line 2—2 of Figure 1;

Figure 3 is an end view showing the material entering the side of the device shown in Figure 1;

Figure 4 is an end view showing the material discharge side of the device shown in Figure 1;

Figure 5 is an isometric view showing a punch press and the material handling device in operative relation to each other;

Figure 6 is a diagrammatic wiring diagram showing the preferred electrical connections used between the press and material handling device; and

Figure 7 is a side elevation of the side member showing the guide pin operating in the slot to move the slider and stop arm down and away from the end of the table.

2

Similar reference numerals indicate the same parts throughout the drawings.

In the construction shown in the drawings a base 10 supports a motor 11 used to rotate a roller 12 preferably of a resilient material to frictionally contact a Venetian blind slat 13 at predetermined intervals and move it rapidly away from a punch press 35 or other device the handler operates with.

A bracket 14 is mounted on the base 10 and pivotally supports one end of a table 15 at one end by a pin 16, so that the unsupported end 34 of the table will normally drop to allow the roller 12 to project through a cut-out portion 17 in the table and frictionally contact the slat 13 and move it along the table away from the machine it operates with in a manner to be explained later. The table 15 is provided with a guide slot 18 to guide the slat 13 edgewise, while the projections 19 at the top of the slot 18 prevent the slat from rising out of the guide slot. The table is normally supported above the top of the motor roller 12, by an adjusting screw 20, which merely contacts the free end of the table, as shown in Fig. 2, and which is adjustable in an arm 21 attached to a slider 22 that reciprocates between guides 23 attached to side members 24. A switch arm 25 is pivotally connected to the slider 22 and when depressed by the oncoming slat 13 it closes a switch 26. The switch arm 25 is normally kept in an extended position by a spring 27 allowing the switch 26 to remain normally open. Springs 28 keep the slider 22 and table 15 in raised position until lowered by a link 29 connected to a solenoid 30. Guide pins 46a are attached to the sides of the slider 22 and are guided in slots 47 positioned in the side members 24 and pull the slider and switch arm 25, up and towards the stopped slat 13 to start the operation of the machine. A bridge member 31 attached to the table 15 supports a tensioning roller 32 having an adjustable pressure applicator 33 for controlling the pressure applied to the slats 13 as they pass over the motor roller 12. The upper ends of the slots 47 limit the upward movement of the slider and the parts carried thereby. In raised position, the top of the slider projects slightly above the free or unpivoted end of the table into the path of an oncoming slat or strip.

A button 37 extends through a slot, in one of the projections 19, into the guide slot 18. The button is secured to the outer end of a rod 39 and a spring 41, as shown in Fig. 3, surrounds the outer end of the rod 39. The spring reacts against a part of the bridge member and urges the rod outwardly to permit the relay hold switch 50 to be held normally open.

The arrangement shown in Fig. 5 includes a punch press 35 and the slat or strip handling device, already described. The punch press is located adjacent to said device and includes a trough in alignment with the guide slot 18. The arrangement operates as follows:

A slat or other similar strip to be operated upon is slid through the trough in the punch press and into the guide slot 18, until the forward end of such strip touches the switch arm 25 and closes switch 26. Such contact 60 momentarily stops further travel of the strip. As said end of the strip approaches the switch arm 25, it engages button 37 and depresses rod 39, thereby closing relay switch 40. Assuming that the main switch 42 has been closed, motor 11 will be running and rotating roller 12. 65 Closing of switch 26 closes a relay 44 and thereby causes one revolution of a crankshaft (not shown) in the punch press. Such rotation of the crankshaft causes the plungers in the punch press to reciprocate and perforate the strip portion in the trough of said press. A cam 36, affixed to the crankshaft, turns with the latter and the dwell portion of the cam is moved away from relay switch 43 and the high portion of the cam closes said switch. Closing

3

of switch 43 energizes the solenoid of stop relay 46 and through the latter causes the solenoid 30 to be energized. Solenoid 30 now pulls the slider downwardly out of the path of the strip. As the slider 22 is lowered, the free end of the table swings downwardly slightly until the underside of the strip engages roller 12. Such engagement, even in the absence of members 31, 32 and 33, would force the strip against members 19 and stop further downward swinging of the table. However, proper tensioning of the spring shown in the pressure applicator 33 assists the roller 12 in so supporting table 15, through contact with the strip, that the latter may pass through the guide slot without having the edges of the strip marred by contact with the elements 19. After the strip, due to the lowering of the top of the slider and the parts carried thereby out of its path, has passed through the guide slot 18, spring 41 moves rod 39 outwardly with respect to relay switch 40 and as a result solenoid 30 is deenergized and springs 28 raise the slider 22 and consequently table 15 to their original positions. Of course, any strip or slat in guide slot 18 will prevent outward movement of rod 39 and opening of relay switch 40.

At the end of each revolution of the crankshaft of the punch press, the dwell portion of cam 36 comes opposite the switch 43 and allows the latter to open. A new cycle of operation of the apparatus shown in Fig. 5 may then be initiated by pushing a slat or other strip through the trough of the punch press and the guide slot 18 until further travel of the strip is stopped by contact of the leading end thereof with the switch arm 25 and depression of the latter to close switch 26.

While but one general form of the invention is shown in the drawings and described in the specification, it is not desired to limit this application for patent to this particular form, as it is appreciated that other forms of construction could be made that would use the same principles and come within the scope of the appended claims.

Having thus described the invention, what is claimed is:

1. A strip handling device adapted to remove a slat-like strip from a machine which has performed work on such strip; said device comprising a base; a motor and a roller carried by said base, said roller being coupled to said motor for rotation thereby; a bracket projecting upwardly from said base; a table pivotally supported at one end by said bracket and having a free end; a pair of parallel projections carried by and cooperating with the top of the table to form a guide slot across said top; said table having an opening therein registering with said slot and located to overlie said roller and, upon downward movement of the free end of the table, to permit said roller to project therethrough into said guide slot; a pair of parallel members, projecting upwardly from said base slightly beyond said free end of the table; a slider; means resiliently supporting said slider from said parallel members for reciprocation therebetween; guide members carried by said parallel members for guiding said slider during such reciprocation; support means projecting from said slider and removably engaging the free end of said table for raising the table to its uppermost position; a switch carried by said slider; a switch closer movable to close said switch, said switch closer being carried by said slider at the top thereof and arranged to extend above the free end of the table at the end of said guide slot when the slider is in its uppermost position; a relay switch supported from said base in a position alongside a side edge of said table; a switch rod carried by said table and having one end resiliently projectable into said guide slot to be depressed by a strip therein, the opposite end of said rod being adapted, when the rod is depressed, to close said relay switch; a solenoid connected with said slider to lower the same, to remove said switch closer from its position at the end of the guide slot and

disengage said support means from the free end of said table; and current conducting means connecting the relay switch to said solenoid.

2. A device of the type set forth in claim 1, which includes a bridge member carried by said table, a roller; and means connecting the last mentioned roller to said bridge and holding the last mentioned roller in position to exert pressure on the top of a strip having its bottom side engaged by the first mentioned roller.

3. A device of the type set forth in claim 2, which includes means for adjusting the pressure exerted by the last mentioned roller on the top of the strip.

4. The combination, with a punch press, of a strip handling device arranged to remove strips from said press after the latter has perforated such strips; said press including a casing; a crankshaft in said casing; plunger means connected to said crankshaft for reciprocation thereby; a cam mounted on said crankshaft and positioned exteriorly of said casing; and a trough for receiving strips to be perforated by said plunger means; said strip handling device including a base; a motor and a roller mounted on said base, said roller being connected to said motor for rotation thereby; a table having one end pivotally connected to said base and having a free end; means carried by said table for cooperating with the top thereof to form a guide slot in alignment with the trough of said press; a slider; a pair of parallel members projecting upwardly from said base; springs suspending said slider from said parallel members for reciprocation therebetween in a plane slightly beyond that of the free end of the table; support means projecting from said slider and detachably engaging the free end of the table; a switch; a switch closer carried by said slider for movement from a first position extending slightly above the free end of the table at a point near the end of said slot to a second position below the top of said table clear of the guide slot; a relay; means supporting said relay from said base at a location alongside one of the side edges of said table; a switch rod carried by said table and having one end resiliently projectable into said guide slot for depression by a strip therein, said rod having its opposite end arranged to close said relay when the rod is depressed; a solenoid carried by said base and connected to said slider for drawing the latter downwardly to withdraw the switch closer from the path of a strip in said guide slot; current conducting means connecting said relay to said solenoid; a switch having the opening and closing thereof controlled by said cam; a holding relay connected to the last mentioned switch and to the first mentioned relay; said table having an opening therein arranged to overlie said roller when the table is in its uppermost position and to permit the projection of the roller into the guide slot when the table is lowered; said switch closer in its upper position being adapted to stop the travel of a strip through said trough and said guide slot to position such strip for perforation by said plunger means and then initiate a sequence involving a revolution of said crankshaft and the closing by said cam of the switch controller thereby, the energizing of the holding relay, the energizing of the relay connected to the solenoid and pulling by said roller of the perforated strip from the punch press.
